COLLAPSIBLE PACKAGE CARRIER

Laura E. Mattoon, San Francisco, Calif.

Application March 2, 1942, Serial No. 432,935

4 Claims.

(Cl. 280—51)

This invention relates to improvements in package carriers, and more particularly to a collapsible wheeled carrier which may be readily collapsed into a compact form when it is to be carried by hand, and which may be extended into an elongated wheeled container when it is to be moved from place to place during a shopping tour.

An object of my invention is to provide an improved package carrier having a construction capable of being carried as a handbag when empty or when partially filled, and which may be extended and wheeled along the ground when filled.

Another object of my invention is to provide a package carrier of the kind characterized, consisting of a collapsible frame having a foldable bag mounted thereon.

While I show and describe a package carrier considered to be a preferred embodiment of my invention, it is to be understood that changes as to form, proportions, and minor details of construction may be made within the scope of the claims without departing from the spirit of the invention.

In the accompanying drawings:

Fig. 1 is a perspective view of my improved package carrier, showing a side partially open and also showing the same fully extended and in a form whereby it may be wheeled about;

Fig. 2 is another perspective view of the package carrier, showing the same collapsed and in a compact form whereby it may be carried as a handbag;

Fig. 3 is a sectional view taken vertically through the carrier when in the form shown in Fig. 2;

Fig. 4 is a perspective view of the collapsible frame in an extended or unfolded form, showing by the dotted lines the relative positions of the various parts when they are moved to partially collapsed positions; and

Fig. 5 is a longitudinal section taken vertically through the carrier when in a fully extended or unfolded form.

Referring to the drawings, the numeral 1 designates a lower U-shaped frame member having a plurality of casters 2 depending therefrom. The upwardly disposed legs of the U-shaped frame member are pivotally mounted on a transversely disposed rod 3. Also pivotally mounted on the rod 3 are two side frame members 4 which are preferably of the same width as the U-shaped frame member 1. Sleeves 5 slidably carried by the side frame members 4 are adapted to extend

over the upwardly disposed ends of the U-shaped frame member 1 when the said side members and the upwardly disposed legs of the U-shaped frame member are in alignment. When the sleeves are in positions whereby they extend around the lower ends of the side frame members 4 and the upper ends of the upwardly disposed legs of the U-shaped frame member 1, the said frame members are held in rigid positions with respect to each other, and when so positioned the lower part of the frame is prevented from pivotally moving about the rod 3.

Pivots attached to the upper ends of the side frame members 4 are two U-shaped elements 6, both of which are capable of being moved to positions where they extend upwardly in oppositely inclined directions, as shown by the full lines in Fig. 4, or they may be moved to downwardly disposed positions with their transverse central parts extending outside the U-shaped member 1 and in adjacent and parallel relation to the corresponding part thereof as shown by the broken lines in the same figure.

Pivots mounted on the side frame members 4 near their upper ends, as by means of thumb screws 7, are two keepers 8, which when in upwardly extended positions as shown by the full lines in Figs. 4 and 5, serve to support the U-shaped elements 6 in upwardly disposed inclined positions. The keepers may be moved to positions alongside their associated side frame members as shown by the broken lines in Fig. 4 when the frame and its bag are to be folded into a compact form. The thumb screws 7 serve to maintain the keepers 8 in either of the two positions with respect to the side frame members 4. The U-shaped elements 6 are preferably made from heavy semi-rigid flexible steel wire, and being capable of bending slightly, the keepers 8 may be readily brought into engaging or non-engaging positions with respect thereto. Pivots mounted at their ends on the transverse rod 3 are two U-shaped wires 9 which have a fabric piece 10 secured thereto. The fabric piece 10 forms a bottom support for the inside of the bag, as will be later described.

Supported on the frame is a foldable bag 11 which at its lower closed end is provided with suitable openings for the side legs of the U-shaped member 1 to extend through. The fabric piece 10 is adapted to extend interiorly across the lower end of the bag, and snap fasteners 12 serve to secure the opposite ends of the said fabric piece to the opposite sides of the bag, as shown in Fig. 5. The fabric piece when attached

to the sides of the bag provides an inner bottom support for supporting the packages dropped into the bag, thereby providing means whereby the weight of the packages or articles carried may be supported on the frame rather than on the bottom of the bag proper.

The opposite sides of the bag 11 near its upper area is slit and its upper end is looped and is secured to the transverse parts of the U-shaped elements 6. Secured to the upper end of the bag at points where it is looped and is secured to the U-shaped elements 6, are two handles 13 which are preferably made from the same material from which the bag is constructed.

Secured to the upper end of the bag at points where the U-shaped elements extend through the looped parts are two depending panels 14 which are made preferably from the material from which the bag proper is made. These panels are provided at their side edges and at their lower ends with hookless fastening means 15 by means of which they may be attached together. When the bag is in an unfolded position as shown in Fig. 5, the lower fastening means 15 is detached, thereby leaving an opening at the lower ends of the panels 14 through which packages inserted into the bag may drop onto the bottom piece 10.

When the bag is thus unfolded the frame and the bag are in extended positions and the U-shaped elements 6 are separated at their upper ends, thereby providing means for maintaining the bag in a position with its upper end open. The device may be wheeled about by suitably pulling on one of the handles 13.

When it is desired that the device be collapsed so it may be carried as a handbag, the sleeves 5 are first slid upwardly to permit the U-shaped member 1 to be swung over to a position where the casters 2 and the central part thereof are in engagement with a side of the bag. The keepers 8 are then disengaged from the U-shaped elements 6, and after the unfastening of the hookless fasteners 15 at the sides of the panels 14, the said elements are swung outwardly in opposite directions and then toward each other to positions where their central parts are in close proximity to one another. When so positioned the handles 13 may be both grasped by a person's hand. The side and bottom fastening means 15 are thereupon fastened together, thus forming a shortened handbag having a top opening at points between the handles.

It will be seen that my improved package carrier is capable of holding and conveniently transporting a number of packages or articles of merchandise which might otherwise be too heavy to comfortably carry by hand.

Having described my invention, what I claim is:

1. A package carrier comprising a collapsible frame having side members and a U-shaped lower part pivoted to the side members, rotatable wheels carried by the U-shaped part of the frame, a bag supported by the frame having inner de-

pendings panels which are adapted to be positioned outside the bag when the U-shaped part of the frame is in a collapsed position with respect to the side members, and means for fastening the panels together after they are positioned outside the bag, and handle means secured to the upper end of the bag.

2. In a package carrier, a frame formed with side members and a depending pivoted bottom member adapted to be swung from an extended normal position to a collapsed position with respect to the said side members, roller means carried by the bottom member, a foldable bag extending over and supported by the frame, having means in its bottom for the outward projection of that part of the bottom member of the frame which carries the roller means, a pair of spaced rigid members pivoted to the upper ends of the side members of the frame, the said rigid members being secured to the upper end of the bag and so arranged when in certain positions to normally hold the upper end of the bag in an open position, extensions on the upper end of the bag for extending around the bag and frame when they are in a collapsed form, and means for attaching the extensions together at their sides and at their free ends, and handle means on the bag.

3. In a package carrier, a frame formed with foldable parts adapted to be collapsed into folded positions or to be unfolded and arranged in extended positions, means for maintaining the parts in relative rigid positions when they are extended, roller means on the frame for engaging with a floor or supporting surface, a collapsible bag extending over and supported by the frame, means carried on the frame for normally holding the upper end of the bag in an open position, and flexible extensions on the upper end of the bag, the said extensions being arranged to be positioned inside the bag when the frame and bag are unfolded and when the bag and frame are folded to be positioned outside and around the said bag and frame.

4. In a package carrier, a frame formed with pivoted attached parts adapted to be collapsed into folded positions or to be unfolded and arranged in extended positions, means for maintaining the frame parts in substantially rigid positions with respect to each other when they are extended, roller means carried by the frame, a collapsible bag supported on the frame having its lower end closed and its upper end open, extensions on the upper end of the bag having means for fastening their sides and free ends together, the said extensions being normally positioned inside the bag when it and the frame are in unfolded positions, and the said extensions being arranged so they may be positioned outside the folded bag and the folded frame whereby a carrying device of reduced size may be provided when the bag and frame are in folded positions, and handle means connected to the bag.
